THERMOSTATIC SWITCH

Robert N. Levinn, Catskill, N.Y., assignor to American Thermostat Corporation, South Cairo, N.Y., a corporation of New York

Filed July 2, 1963, Ser. No. 75,637

Term of patent 14 years

(Cl. D26—13)

FIG. 1

FIG. 4

FIG. 2

FIG. 3

FIG. 1 is a top plan view of a thermostatic switch showing my new design;

FIG. 2 is a side elevational view thereof;

FIG. 3 is a bottom plan view thereof; and

FIG. 4 is an end elevational view thereof taken from the left hand end of FIG. 1.

The dominant portions of my new design are shown in solid lines.

I claim:

The ornamental design for a thermostatic switch, as shown and described.
